UNITED STATES PATENT OFFICE.

CARL A. MAIENSCHEN, OF EVANSVILLE, INDIANA.

SHADE AND CURTAIN BRACKET.

Application filed June 20, 1921. Serial No. 478,973.

To all whom it may concern:

Be it known that I, CARL A. MAIENSCHEN, a citizen of the United States, residing at Evansville, in the county of Vanderburg and State of Indiana, have invented certain new and useful Improvements in Shade and Curtain Brackets, of which the following is a specification, reference being had to the accompanying drawings.

This invention relates to window shade and curtain brackets and has for its object to provide a bracket of this character that can be readily applied to any window, 15 to properly support a window shade and curtain.

It is also an object of the invention to provide a shade and curtain bracket of this character embodying a supporting arm with 20 which a curtain holding member is detachably engaged.

It is another object of the invention to provide a bracket of this character embodying a supporting arm to which one end of 25 the curtain holding member is detachably connected, the opposite end of the curtain holding member resting upon the arm.

It is still a further object of the invention to provide a bracket of this character 30 embodying a supporting member with which either a curtain holding arm or a curtain rod may be detachably connected and supported at both end portions.

With these and other objects in view the 35 invention consists in the improved construction and arrangement of parts to be hereinafter more particularly described, fully claimed and illustrated in the accompanying drawings, in which:

40 Figure 1 is a top plan view of a window shade and curtain bracket constructed in accordance with an embodiment of the invention, the shade roller and curtain rod being shown in dotted lines,

45 Figure 2 is a perspective view of another form of the invention,

Figure 3 is a perspective view of the detachable holding members disclosed in Figure 1.

50 Referring to the drawings, 5 and 6 designate supporting arms adapted to support a shade roller and curtain rod or curtain holding means. As each supporting arm is similar in construction, the description 55 of one will suffice for both.

The supporting arm consists of a strip

of material having one end portion extended at right angles to the body portion of the strip to provide a foot 8 adapted to be secured to a window casing, the opposite end portion of the strip being extended at right angles and in the opposite direction of the foot 8 to provide a supporting finger 9, said finger having a key hole slot 10 provided in its upper surface adjacent the junction of the finger with the body portion of the strip. The intermediate portion of the strip 5 has an opening 11 for the reception of one end of a shade roller, and an opening 12 which is disposed adjacent the foot of the arm, the purpose of which will be hereinafter described.

In order to support a curtain rod or pole, there is provided a novel holding member for detachable connection to each of the 75 arms 5 and 6. Each holding member consists of a length of material 13, having its end portion 14 extended at right angles to the length and adapted to be extended through the opening 12 of the arm to connect the member to the arm. The opposite end portion of the member is extended at right angles as at 15 to the arm and in the opposite direction to the end portion 14, then upwardly and downwardly to provide a finger 16. The remainder of the arm is then extended substantially in parallel relation as at 17 to the length 13 and then upwardly as at 18, the last mentioned portions cooperating with the finger 16 to form 90 a seat for the reception of a conventional form of curtain rod. It is of course obvious that the seat can be made in any size desired, according to the diameter of the curtain rod.

The body portion 13 of the length is adapted to be disposed in parallel relation to and closely adjacent the body portion of the supporting arm, while the portion 15 is extended through the key hole slot 10 and disposed parallel to the finger 9, thereby positioning the socket member in offset relation to the arm. One of the curtain holding means is provided for each of the supporting arms 5 and 6. The holding member engaged with the arm 6 is constructed similar to the holding member 13, with the exception that the members extend in opposite directions so as to position each of the socket members on the adjacent outer side of the supporting arms. With this means, a curtain rod of any construc-

tion may be efficiently supported by the bracket. It will be noted that the foot 8 of the supporting arm 6 extends toward the foot 8 of the supporting arm 5, while the 5 finger 9 of the supporting arm 6 extends in the opposite direction to the finger 9 of the supporting arm 5.

In connection with each of the supporting arms 5 and 6, a single curtain rod may 10 be used in place of the holding members. This rod includes telescopic sections 19 and 20, the end portion of the section 19 being extended in angular relation as at 21 to the section 19, and then in parallel relation 15 as at 22 to the section 19, and then at right angles to the portion 22, as at 23, the extremity of said end being extended in parallel relation to the section 19 to provide a finger 24 adapted to pass through the 20 opening 12, the portion 23 being disposed in the key hole slot 10. The end portion 25 of the section 20 is similar in construction to the end portion of the section 19, the finger formed on the end portion of the 25 section 20 being adapted to extend through the opening 12 provided in the arm 6. By this novel construction, the telescopic rod is supported in the same manner as the conventional form of curtain rod is supported 30 by the holding members.

From the foregoing, it will be readily seen that this invention provides a novel form of shade and curtain bracket capable of being attached to any window casing for 35 not only supporting a shade roller in the usual manner between the end portions of

the arms 5 and 6, but also for supporting a curtain rod and curtain regardless of the weight of the curtain, as the supporting members or ends of the telescopic rods are connected to one of the ends of the arms and supported or braced by the opposite ends of the arms, so that regardless of the distance between the curtain and the window casing, there is no danger of the curtain accidentally falling. In addition to this, the length of the arms 5 and 6 may be increased to permit the use of two shade rollers if so desired without interfering with the curtain holding members.

What is claimed is:—

A bracket of the character described comprising a substantially Z-shaped supporting arm, one end portion of said arm being secured to a support, the opposite end portion having a recess extending laterally thereof, and a curtain holding member consisting of a length of material having one end portion thereof pivoted to the arm adjacent the first mentioned end portion of the arm and arranged for vertical movement relative to the arm, said holding member extending laterally of the second mentioned end portion of the arm and through the recess, said second mentioned end portion of the arm limiting movement of the curtain holding member in one direction.

In testimony whereof I hereunto affix my signature.

CARL A. MAIENSCHEN.
